UNITED STATES PATENT OFFICE.

FRANK W. HEETER AND TERRY E. HEETER, OF TOLEDO, OHIO.

FOLDING MACHINE.

Application filed February 18, 1922. Serial No. 537,658.

To all whom it may concern:

Be it known that we, FRANK W. HEETER and TERRY E. HEETER, citizens of the United States, and residents of Toledo, in the county of Lucas and State of Ohio, have invented certain new and useful Improvements in Folding Machines, of which the following is a specification.

This invention relates to an improvement 10 in machines for forming and folding paper napkins or similar articles.

The object of the invention is to provide a machine of this character which mechanically forms and folds paper napkins or the 15 like in such a manner as to eliminate the necessity of any handling of the napkins thereby insuring a sterile and germ-proof product; which is automatic and continuous in its operation so as to be capable of quantity 20 production on the desired scale; and which is of simple and durable construction, reliable and safe in operation and easy and inexpensive to manufacture and operate.

Other objects and advantages of the invention 25 reside in certain novel features of construction, combination and arrangement of parts which will be hereinafter more fully described and particularly pointed out in the appended claims, reference being had to 30 the accompanying drawings forming part of this specification, and in which:

Figure 1 is a plan view of the invention;

Figure 2 is a side elevational view thereof;

Figure 3 is a view in longitudinal vertical 35 section on line 3—3 of Figure 1;

Figure 4 is an end elevational view, looking from the left of Figure 3, parts being omitted for the sake of illustration;

Figure 5 is a detail view in side elevation 40 of the forming shell and coacting plunger;

Figure 6 is a detail view, in plan, of the forming shell;

Figure 7 is a detail view, in plan, of the forming plunger and associated structure;

Figure 8 is a fragmentary perspective 45 view of the actuating means employed for the cutter mechanism;

Figure 9 is a diagrammatic view, illustrating the lines of fold of the napkin;

Figures 10 and 11 are elevational views, 50 illustrating the napkin as folded in the successive stages of the operation;

Figure 12 is a view in central transverse 55 vertical section, showing in detail the construction of the folding rollers; and

Figure 13 is a detail view in side elevation

of one of the folding rollers illustrated in Figure 12.

Referring to the drawings wherein for the sake of illustration is shown the preferred embodiment of the invention, the numeral 10 designates generally the frame of the machine. A table 11 is mounted on the frame, and to this table the web of the paper from which the napkins are to be 60 formed and folded is fed.

Means is provided for feeding the web of paper to the table 11 and includes a supply roll 12 rotatably mounted at one end of the machine. A guide plate 13 is operatively arranged with respect to the supply roll and guides the web of paper to the feed rollers 14 and 15 rotatably supported on the frame. One of the feed rollers, preferably the roller 15, is mounted in adjustable bearings designated at 16, whereby it may be adjusted toward and away from the feed roller 14. The feed rollers are rotated so as to engage and feed the web of paper from the supply roll 12 to the table 11 and for this purpose 70 the feed roller 14 has connected thereto a gear 17 which meshes with an intermediate gear 18 from which it is driven.

Cutting mechanism is provided and is arranged between the feed rollers and the table 80 11 and operates to sever the napkin from the web of paper after the length of paper which constitutes the napkin has been fed to the table. This cutting mechanism preferably includes a cutter block or anvil 20 secured upon one end of the table 11 and over which the web of paper is fed. A cutter 21 is mounted above the cutter block 20 and is adapted to partake of vertical reciprocatory movement. On the downward movement of the cutter 21 it coacts with the cutter block 20 to effect the cutting action. Compression coil springs 22 mounted upon supporting rods 23 of the cutting mechanism tend to maintain the cutter 21 raised and out of engagement with the paper. A rock shaft 25 is journaled in pedestals 26 mounted on the frame and has fixed thereto a rock arm 27 suitably connected at one end with the cutter 21 and having at its other end a wiping toe 28 engageable with a wiping cam 29 fixed to a rotating cam shaft 30 journaled in suitable bearings provided therefor in the pedestal 26 and driven by a gear 31 meshed with and rotated from the intermediate gear 18. The cutter 21 is thus actuated at predetermined intervals in accordance with the movement 100 105 110

of the feed rollers so that when a length of paper sufficient to constitute a napkin has been fed onto the table the cutter 21 is depressed by the rock arm 27 to sever the 5 length constituting a napkin from the web. The napkin thus formed is deposited on the table 11 ready for the creasing and folding operation.

A forming bed 35 of hopper or funnel-like 10 formation depends from the table 11, the table having an opening 36 coextensive with the upper end of the forming bed. The forming bed contracts toward its lower end and the bottom or lower end thereof is 15 provided with an elongated slot 37 extending longitudinally of the forming bed and transversely of the table 11. Creasing blades or ribs, indicated at 38 are provided on the forming bed and as shown in Figure 20 6 are arranged in sets of two at each end thereof and extend from the top of the bed to the slot 37 in its bottom.

A plunger, designated generally at 39 coacts with the forming bed, and comprises a 25 crosshead 40 extending transversely above the table and mounted for reciprocatory movement on guide rods 41 upstanding at both sides of the frame. A plurality, preferably six, creasing blades or ribs 42, depend 30 from the crosshead and terminate at the lower ends in a finger 43 which constitutes an ejector. The blades 42 may be formed by the edges of plates as shown in the drawings. The creasing blades or ribs 42 of the 35 plunger coact with the creasing blades or ribs 38 of the forming bed to produce or form the creases or lines of fold of the napkin. As shown in Figure 9, three blades 42 or three edges of the plates making up the 40 blades coact with each set of blades 38, the blades 42 producing outward folds or creases along the lines *a*, *b* and *c* which extend from the center to each side of the napkin and the blades 38 producing inward folds or creases 45 along lines *d*, *e* which also extend from the center to each side of the napkin.

At the upper ends of the guide rods 41 brackets 44 are arranged and retractile coil springs 45 are adjustably secured at their 50 upper ends to the brackets, as at 46, and are also secured at their lower ends to the cross head 41. These springs 45 serve to maintain the plunger in retracted position above the table 11 so that it does not interfere with 55 the delivery of the napkins thereto, and these springs in conjunction with mechanism to be hereinafter described also function as means for effecting a quick return of the plunger.

When the plunger 38 descends its finger 43 60 engages the napkin then lying on the table 11 and carries the napkin with it and onto the forming bed. The ribs of the bed and of the plunger then act upon the napkin to crease or plait it thus forming the lines of

fold and the finger 43 eventually carries a portion of the napkin through the slot 37.

Below the forming bed a pair of folding rollers designated at 50 and 51 are arranged, the rollers being in rotatable contact with each other and having their line of contact lying in the same vertical plane as the center or longitudinal axis of the slot 37 of the forming bed. The rollers 50 and 51 are carried on shafts 52 and 53, respectively, which are arranged in bearings provided therefor in the frame 10 and project slightly beyond the frame at one side thereof. Twin gears, designated at 54 and 55 are fixed to the projecting ends of the shafts 52 and 53, respectively, and constrain the folding rollers to corresponding motion. As shown in Figure 2, the twin gear 54 is also meshed with the intermediate gear 18 and serves to rotate this intermediate gear as will be presently described. When the plunger 38 has completed its down stroke the napkin has been completely creased or plaited and the finger 43 of the plunger has carried a portion of the napkin, preferably the center, through the slot 37 and in between the folding rollers 50 and 51 which are provided with arcuate slots 56 and 57 in their peripheries for the purpose of accommodating the finger 43 at this time. The arcuate slots 56 and 57 are of identical construction and each extends for an angular distance of approximately 90° of its roll and has an inclined bottom wall of varying depth, as shown in the drawings. These slots 56 and 57 accommodate the finger 43 of the plunger and at the same time permit the folding rollers to grip the napkin carried by the finger and to draw it through the slot 37 of the bed and in between the folding rollers wherein the napkin is folded or pressed on the lines of fold produced by the plunger and forming bed.

It is obvious that as soon as the folding rollers grip the paper or napkin the finger 43 of the plunger must at once be withdrawn from the slots 56 and 57 and for this purpose the operating mechanism for the plunger is such as to provide for a quick return movement thereof.

This operating mechanism includes driving arms 58 fixed to the ends of the shaft 53 of the roller 51 and carrying crank pins or driving pins 59 at their outer axis with which the hooked ends 60 of swinging pitmen 61 are adapted to be intermittently and 115 releasably engaged, the upper ends of the pitmen 61 being pivotally connected, as at 62, with the cross head 40 of the plunger and these pitmen 61 operating in guide brackets or straps 63. As the driving arms 120 swing downwardly in a clockwise direction, as viewed in Figure 2, their pins 59 engage the hooked ends 60 of the pitmen 61 and cause the plunger to partake of its 125 downward stroke. When this down stroke 130

of the plunger has been completed, to complete the plaiting or creasing operation, the pins 59 ride off of the hooked ends 60 and the springs 45 then at once effect the quick 5 return of the plunger, the driving arms being idle during their upward movement but being again effective on their downward movement to again depress the plunger and so on in continuous and successive cycles.

10 As the napkin passes between the folding rollers 50 and 51 it curves down under and away from the roller 50 and its free end then slides along the upper surface of the finishing rollers, designated at 60^a and 61^a

15 journaled in suitable hanger bearings 62^a and 63^a and having their axes extending at right angles to the axes of the folding rollers 50 and 51 and also being displaced longitudinally with respect to the rollers 50 and 20 51 so as to compensate for the curving motion of which the napkin partakes when it is delivered from the rollers 50 and 51. The free end of the napkin slides along these rollers 50 and 51 and when the napkin is 25 entirely released from the folding rollers 50 and 51 it drops on the finishing rollers and is redoubled by them along line f (see Figure 9). One of the finishing rollers carries a worm wheel 65 with which a worm gear 30 66 fixed to one end of a shaft 67 meshes, the opposite end of the shaft 67 having a pinion 68 fixed thereon and meshed with a gear 69 of a gear train including the gear 69 and a relatively large gear 70 which is meshed 35 with the gear 69 and also with the twin gear 55 from which the gear train receives its motion.

A drive shaft 75 is journaled in suitable bearings 76 provided therefor in the frame 40 10 and carries a worm 77 operatively engaging the worm gear 78 fixed to the shaft 53. This drive shaft 75 may be driven from an electric motor or any other suitable source of power and it serves to drive the 45 shaft 53 and consequently the twin gears 54 and 55 from whence the other gears of the machine are driven, it being understood that the twin gear 54 is fixed to the shaft 53.

In operation the web of paper travels from 50 the supply roll 12 over the guide plate 13 and is delivered by the feed rollers 14 and 15 across the cutting block or anvil to the table 11. When a length of paper sufficient to constitute a napkin has been fed to the table 55 11 the cutter 21 is actuated to sever the length from the web and allow the napkin to settle or to be deposited on the table 11 and overlie the forming bed. The plunger 38 is then moved downwardly as the pins 59 of the driving arms 58 engage the hooked ends 60 of the pitman 61 at this time and move the plunger down against the tension of the springs 45. The creasing blades or ribs of the plunger and of the forming bed then coact to plait 60 or crease the napkin and produce the lines

of fold therein and the finger 43 of the plunger pushes the napkin through the delivery slot 37 of the forming bed and into engagement with the folding rollers 50 and 51, the pitman 61 being then released to permit the 70 springs 45 to effect a quick return of the plunger to inoperative position above the table and out of the way of the next length of paper then being fed thereto. The folding 75 rollers fold the napkins on the plaits or creases produced by the plunger and forming bed and deliver it to the finishing rollers which redouble it and complete the folded napkin. This cycle of operations is repeated 80 in rapid succession so as to provide a continuous operation enabling a quantity production of folded napkins on any desired scale.

I claim:

1. In a machine of the character described, a table, a supply roll, feed rollers for delivering a web of paper from said supply roll to said table, a gear for driving said feed rollers, cutting mechanism for severing the length of paper sufficient to constitute a napkin and comprising a cutter and actuating mechanism therefor including a gear, an intermediate gear meshing with the gear of the feed rollers and with the gear of the actuating mechanism whereby the cutter operates in timed relation with respect to the feed 85 rollers, a folding bed depending from the table, a forming plunger cooperable with the forming bed, folding rollers cooperatively arranged with respect to the forming bed, shafts carrying said rollers, twin gears fixed 90 to said shafts, one of said twin gears being meshed with the intermediate gear for driving the same, operating mechanism for the plunger including a crank arm having a crank pin, a pitman connected with the 95 plunger and having a hook end releasably and intermittently engaged with the crank and spring means for effecting quick movement of the plunger, finishing rollers cooperatively arranged with respect to the 100 folding rollers, gearing for driving said finishing rollers from said twin gears, and means for driving one of the shafts of the feed rollers whereby said twin gears and the 105 gears driven therefrom are actuated.

2. In a machine of the character described, a table, means for feeding napkins to said table, a forming bed depending from said table and over which the napkin on the table lies, a forming plunger arranged above said table and cooperable with said bed, folding rollers cooperatively arranged with respect to the forming bed, means for driving said folding rollers, twin gears for constraining said rollers to corresponding motion and 110 operating mechanism for the plunger including a crank arm fixed to one of said twin gears and having a driving pinion and a swinging pitman connected with the plunger and having a hooked end cooperable with 115 120 125 130

the driving pin of the crank arm, and springs for effecting a quick return movement of the plunger.

3. In a machine of the character described, 5 a table, a supply roll, feeding rollers for delivering a web of paper from said supply roll to said table, a gear driving said feed rollers, cutting mechanism for severing a length of paper sufficient to constitute a napkin and comprising a cutter and actuating mechanism therefor including a gear, an intermediate gear engaging the gear of the feed roller and the gear of the actuating mechanism whereby the cutter operates in timed relation with respect to said feed rollers, a forming bed depending from the table, a forming plunger cooperable with the forming bed and folding rollers cooperatively arranged with respect to the forming bed.
- 10 4. In a machine of the character described, a table, a supply roll, feed rollers for feeding a web of paper from the supply roll to the table, cutting mechanism arranged between the table and the feed rollers for 15 severing a length of paper from the web sufficient to constitute a napkin, a forming bed depending from the table and having creasing blades, a forming plunger mounted above the table and having creasing 20 blades cooperable with the creasing blades of the forming bed for creasing the napkin deposited on said table, and folding rollers receiving said creased napkins from said forming forming bed and folding them on 25 said creases.
5. In a machine of the character described, a table, a supply roll, feed rollers for feeding a web of paper from the supply roll to the table, cutting mechanism arranged 30 between the table and the feed rollers for severing a length of paper from the web sufficient to constitute a napkin, a forming bed depending from the table, a forming plunger mounted above the table and co- 35 operable with the forming bed for creasing the napkin deposited on said table, and folding rollers receiving said creased napkins from said forming forming bed and folding them on said creases.
- 40 6. In a machine of the character described, a forming bed having a delivery slot in its bottom wall and provided with creasing blades, a plunger cooperable with said forming bed and provided with creasing 45 blades cooperable with the creasing blades thereof and having a finger constituting an ejector for pushing the napkins through said

60 delivery slot, folding rollers arranged adjacent the delivery slot and having arcuate slots provided in their peripheries for accommodating the finger of the plunger whereby the rollers are adapted to grip the napkin and carry it between them to fold the same, and operating mechanism for the plunger including a quick return movement 65 therefor.

7. In a machine of the character described, 70 a forming bed consisting of a shell of hopper-like form having a slot in its bottom wall and provided with creasing blades, a 75 plunger cooperable with said bed and having creasing blades cooperable with the creasing blades thereof, a finger adapted to push the napkin through said slot and folding rollers arranged below said slot, and adapted to receive and grip the napkin pushed therethrough.

8. In a machine of the character described, 80 a forming bed consisting of a shell of hopper-like form having a slot in its bottom 85 wall and provided with creasing blades, a plunger cooperable with said bed and having creasing blades cooperable with the creasing blades thereof, and a finger adapted to push the napkin through said slot and folding rollers arranged below said slot.

9. In a machine of the character described, 90 a forming bed having its delivery slot in its bottom wall and provided with creasing blades, a plunger cooperable with said forming bed and provided with creasing blades cooperable with the creasing blades thereof and having a finger constituting an ejector 95 for pushing said napkins through said delivery slot, and folding rollers arranged adjacent the delivery slot and having arcuate slots provided in their peripheries for accommodating the finger of the plunger when it projects through the creases of the delivery slot in the forming bed whereby the 100 rollers are adapted to grip the napkin and carry it between them to fold the same.

10. In a machine of the character described, 105 a table, means for feeding napkins to said table, a forming bed depending from said table having creasing blades, a forming plunger arranged above said table and cooperable with said bed and having creasing blades cooperating with the creasing blades of the bed, and folding rollers receiving the creased napkins and folding them on said creases.

TERRY E. HEETER.
